ATTORNEY.

UNITED STATES PATENT OFFICE.

WILLIAM M. POTTER, OF SYRACUSE, NEW YORK, ASSIGNOR TO E. C. STEARNS & CO., OF SYRACUSE, NEW YORK.

FLOOR-HINGE.

No. 802,313.

Specification of Letters Patent.

Patented Oct. 17, 1905.

Application filed October 9, 1902, Serial No. 126,541.

To all whom it may concern.

Be it known that I, WILLIAM M. POTTER, a citizen of the United States, residing at Syracuse, in the county of Onondaga and State of New York, have invented certain new and useful Improvements in Floor-Hinges; and I do hereby declare the following to be a full, clear, and exact description of the invention, such as will enable others skilled in the art to which it appertains to make and use the same.

My invention relates to floor-hinges, and has for its object to produce a double-acting floor-hinge of strong, simple, and economical construction and effective operation; and it consists in the arrangement of parts and details of construction herein described.

In the drawings herewith, Figure I is a side elevation of a door fitted with my hinge. Figs. II and III are respectively side elevation and top plan of my hinge. Figs. IV and V are vertical sections showing the parts in different positions. Fig. VI is a cross-section on line VI of Fig. IV. Fig. VII is an enlarged elevation of the sliding block and roller detached.

In the figures, 1 indicates the door hung on top hinge 2 and provided at the bottom with bearing 3, engaging with squared head 4 of hinge-pin 5 of the floor-hinge, fitted to suitable cavity in base-board or floor 6. The hinge consists of cylindrical shell 8, of cast metal or other suitable material, provided with integral socket 9, fitted with ball-bearing 10 for lower end of pin 5, having shoulder 11 near upper end fitting upper socket 13 on cap-plate 14, secured to flange on upper end of shell by suitable screws. With integral cam 15 on the pin, having corresponding inclination on both sides, engages antifriction-roller 16, journaled in sliding block 17, cut out on each side to fit guides 18 and carrying on its upper cylindrical end 19 the spiral spring 21, engaging with the shouldered collar 22, adjusted by screw 23, having its threaded shank 24 fitted to the collar and its shoulder 25 engaging with the upper surface thereof. That the tension of the spring may be easily adjusted the screw-head extends upwardly through the cap-plate and the finishing-plate 27. At lower point of cam is preferably formed pocket 28 for the roller, and the shell may be more or less filled with oil, as shown, for permanent lubrication.

The operation of my spring is best under-

stood from Figs. IV and V. In the former the parts are in the closed position of the door. As it is opened in either direction the cam is rotated by the door and forces the roller to ride up its incline in either direction toward its highest point, as shown in Fig. V, compressing the spring. When the door is released, the pressure of the spring forces the roller down the incline, returning the door to closed position.

Having thus described my invention, what I claim as new, and desire to secure by Letters Patent, is—

1. In a floor-hinge, the combination with the door, of a shell fitted to a cavity in the floor below the door, a vertical hinge-pin journaled in the shell having its upper end in engagement with the door, a ball-bearing arranged in the bottom of the shell, a cap-plate secured to the top of the shell, an integral cam surrounding the hinge-pin having its low point and its high point oppositely arranged, and similar inclinations on both sides, a sliding block fitted to guides in the shell, a projection on the block to engage with the cam, a collar arranged above the block, an adjusting-screw engaging with the said collar, and a spring arranged between the block and the collar.

2. In a floor-hinge, the combination with the door, of a shell fitted to a cavity in the floor below the door, a cap-plate secured to the top of the shell, and a finishing-plate fitted over said cap-plate, a hinge-pin journaled in the shell and engaging with the bottom of the door, an integral cam surrounding the pin, a sliding block fitted to integral guides in the shell having an antifriction-roller engaging with the cam, a collar arranged above the block, an adjusting-screw engaging with said collar and having an upwardly-extending head, and a spiral spring arranged between the block and the collar.

3. In a floor-hinge, the combination with the door, of a cylindrical shell arranged below the door in a suitable cavity, a ball-bearing arranged in the bottom of the shell, a cap-plate secured to the top of the shell, a vertical hinge-pin journaled between the ball-bearing and the cap-plate and having an angular head upwardly extending through the cap-plate in engagement with the door, an integral cam surrounding the lower end of the hinge-pin and having similar inclina-

- tions on both sides between its opposite high and low points, vertical guides in the shell, a sliding block fitted to slide in said guides, an antifriction-roller on said block engaging with the cam, a collar arranged above the block, an adjusting-screw engaging with the said collar and having an upwardly-extending head, and a spiral spring arranged between the block and the collar.
- 10 4. In a floor-hinge, the combination with the door suitably supported, of a cylindrical shell arranged in a cavity in the floor beneath the door, a socket in the bottom of the shell, a ball-bearing arranged in said socket, a cap-plate secured to the top of the shell, a corresponding socket in the under surface of the guide-plate, a finishing-plate fitted over the cap-plate, a vertical hinge-pin journaled in the ball-bearing and the upper socket and
- 15 having an angular head upwardly extending through both plates in engagement with the

bottom of the door, an integral cam surrounding the lower end of the hinge-pin and having similar inclinations on both sides between its opposite high and low points, and a 25 suitable roller-pocket at its low point, of vertical guides in the interior of the shell, a sliding block fitted to said guides, an antifriction-roller arranged on said block to engage with the cam, an adjusting-screw having an 30 integral shoulder and a head upwardly extending through the plates, a shouldered collar supported on said adjusting-screw beneath the shoulder, and a spiral spring adjustably maintained between the sliding 35 block and the collar.

In testimony whereof I affix my signature in presence of two witnesses.

WILLIAM M. POTTER.
